UNITED STATES PATENT OFFICE.

ALONZO KIMBALL MARSH, OF NEW YORK, N. Y., ASSIGNOR TO A. KIMBALL COMPANY, OF NEW YORK, N. Y., A CORPORATION OF NEW YORK.

TYPE CHASE.

Application filed January 24, 1923. Serial No. 614,687.

To all whom it may concern:

Be it known that I, ALONZO KIMBALL MARSH, a citizen of the United States, and resident of New York, county of New York, State of New York, have invented an Improvement in Type Chases, of which the following description, in connection with the accompanying drawing, is a specification, like characters on the drawing representing like parts.

This invention relates to a type chase particularly designed for use in connection with either power or hand operated stamping or marking devices, such as employed in printing or marking tags, marking tickets and any similar work.

The object of the invention is to provide a type chase provided with removable type holders each adapted to receive and support a single line or row of type.

The object of the invention is further to provide such a type chase in which the type holders are constructed so as to be laterally nesting thus to bring the lines or rows of type as close together as possible when required.

The object of the invention is further to provide such a type chase in which the type holders are endwise reversible thus enabling separate lines or rows of type to be set up so as to print with the characters facing in opposite directions.

The object of the invention is further to provide such a type chase in which the several type holders may be secured therein with any desired degree of space between the type holders thus enabling the lines of reprinted matter to be spaced apart as required.

The object of the invention is further to provide such a type chase adapted to utilize detachable type which can be readily changed when it is desired to revise the printed matter and which is of a character to render the use of spacers or feelers unnecessary and more particularly adapted to utilize type having their bodies provided with vertical ribs by means of which the position of the type in the type holder is determined.

These and other objects and features of the invention will appear more fully from the accompanying description and drawings

and will be particularly pointed out in the claims.

While a type chase embodying the invention may be utilized in various printing or marking machines whether power or hand-operated it is for convenience of disclosure herein shown in connection with an ordinary type of hand-operated stamp such as employed in the marking or printing of tags or marking tickets.

In the drawings:

Fig. 1 is a view in perspective of an ordinary form of hand-operated stamp or marking machine in connection with which a type chase embodying the present invention may be utilized;

Fig. 2 is a side elevation of a preferred form of type chase embodying the invention showing a plurality of type holders in place and also type in one of the holders;

Fig. 3 is a top plan view of the construction shown in Fig. 2 with the type removed;

Fig. 4 is an end elevation of the type chase shown in Figs. 2 and 3 together with the platen of the printing or stamping machine into which it fits shown in vertical cross section;

Fig. 5 is a view in cross section taken on the line 5—5 of Fig. 3;

Fig. 6 is a view in perspective of one of the type holders shown in Figs. 2 and 3;

Fig. 7 is a view in perspective of the type holder shown in Fig. 6 looking in the opposite direction;

Fig. 8 is a top plan view of two of the type holders shown in laterally nested position;

Fig. 9 is an end elevation of the construction shown in Fig. 8;

Fig. 10 is a top plan view of two of the type holders shown endwise reversed from the position shown in Fig. 8;

Fig. 11 is an end elevation of the construction shown in Fig. 10;

Fig. 12 is a view in perspective of a type character such as preferably employed in connection with the type chase of this invention.

The type chase, in the preferred form illustrated, comprises essentially a rectangular frame and a plurality of type holders mounted in the frame and extending trans-

versely thereof in desired spaced relation and secured to the frame. Both the frame and the type holders may be made of brass or other suitable metal by any suitable operation.

The frame of the type chase comprises the front end member 1, the rear end member 2 and the side members 3, 4 and 5, 6. The side members are provided with similar longitudinal slots 7 to receive the ends of the type holders. In the construction illustrated the upper portions 3 and 5, or the portions above the slots, of the side members are cast or formed integral or rigid with the end members 1 and 2 while the lower portions 4 and 6, or the portions below the slot are removably secured to the remainder of the structure at each end by screws 8. The upper portions 3 and 5 of the side members extend out laterally of the frame beyond the lower portions 4 and 6 so as to form, with respect to the entire frame, ribs adapted to slide in ways in the side walls 9 of the platen of the press or stamp. The front end member 1 of the frame is provided with a suitable handle 10 by means of which the chase may be slid into and removed from the platen.

The type holders are of similar construction and a preferred form of one is shown separately in perspective in Figs. 6 and 7. It comprises a rectangular body having a rectangular opening 11 extending longitudinally of the body and vertically therethrough. One vertical wall of the body is provided with a longitudinal recess in its exterior face of a size sufficient to receive the other vertical wall thus enabling the holders to be laterally nested. In the construction illustrated this result is secured by forming the body of the type holder at one face with a main bar 12 extending longitudinally of the holder, and consequently transversely of the frame when the holder is in place, and by forming the body of the holder at the other face with a pair of auxiliary bars 13 and 14 secured to the main bar parallel therewith. Thus the longitudinal recess in the one face is formed by the space between the auxiliary bars 13 and 14 and this recess is of a size to receive the main bar 12 of an adjacent holder and thus enable the holders to be laterally nested. The main bar 12 is extended beyond the auxiliary bars so as to provide projections or lugs 15 adapted to fit in the slot 7 of the frame and enable the type holder to be secured in place in the frame. The auxiliary bars 13 and 14 are of such a length as to fit against the inner surface of the side members of the frame when the type holders are in place.

These type holders are designed particularly to be used in connection with type of the general character shown in the patent to Pannier, Jr., No. 1,030,120 granted June 18, 1912 and such as shown in Fig. 12 herein.

Such a type comprises a body portion 16 having the type character 17 at the lower end and an overhanging head 18 at the upper end. At the front the usual indicating groove is provided and also a vertical rib 19 which is for the purpose of locating the type in the holder.

The type holder is accordingly provided on the interior face of the recessed vertical wall, or the wall composed of the auxiliary bars 13 and 14, with vertical longitudinally spaced sockets 20. These sockets are to receive the ribs 19 of the type. While these sockets are shown as extending through the lower auxiliary bar 14 it is unnecessary for them to do so and they are thus formed merely for convenience when a sawing or milling operation is employed.

By forming the type holders with these vertical sockets 20 and using type of the character illustrated in Fig. 12 the setting of the type becomes a very simple operation as the type are merely dropped in place without the necessity of providing spacers or otherwise justifying the type. When in place the overhanging head 18 of the type rests upon the upper surface of the auxiliary bar 13. In this position the type character 17 comes well below the frame of the chase and the extreme upper surface of the type is in alignment with the upper surface of the front end member 1 of the frame as shown in Fig. 2. Consequently, when the type have been set up in the type holders in the frame, the entire frame may be slid into position in the platen of the press and the upper surface of the type and the upper surface of the front end member 1 will be directly under and against the main body 21 of the platen.

By reason of the construction of the type holders so that they may nest laterally it is possible to bring the lines of type held thereby very close together. In Figs. 9 and 10 two similar type holders are thus shown nested. The type holders may also be reversed endwise from the position shown in Fig. 8. Two type holders are shown in the reversed position in Figs. 10 and 11. This causes the lines of type to face in the opposite direction so that the printing of one line will read oppositely to the printing of the other line.

The type holders are placed in position in the frame of the chase with their ends 15 in the groove 7 and with the type holders spaced apart and in similar or reversed arrangement all as required by the matter to be printed. When thus placed in the frame they are separately and individually secured by pins 22 driven through the portions 3 and 5 of the side members of the frame into the projecting lugs or ends 15 of the holders.

Having thus described my invention, what

I claim as new, and desire to secure by Letters Patent, is:

1. A printing chase comprising a rectangular frame having opposite side members provided with similar longitudinal slots, a plurality of type holders each comprising a rectangular body provided with projecting lugs at each end adapted to fit within the slots of the frame and having a rectangular opening extending longitudinally thereof and vertically therethrough, one vertical wall of each holder having a longitudinal recess in its exterior face to receive the opposite vertical wall of another holder whereby the holders may be closely nested to bring lines of type held thereby close together.

2. A printing chase comprising a rectangular frame, a plurality of type holders fitting within and extending transversely of the frame and provided with means for securing the type holders in the frame, each type holder having a rectangular opening extending longitudinally thereof and vertically therethrough to receive and support the type, one vertical wall of each holder having a longitudinal recess in its exterior face to receive the opposite vertical wall of another holder whereby the holders may be closely nested to bring the lines of type held thereby close together.

3. A type holder comprising a rectangular body having a rectangular opening extending longitudinally thereof and vertically therethrough, one vertical wall of said holder having a longitudinal recess in its exterior face of a size sufficient to receive the other vertical wall whereby a plurality of the said holders may be nested.

4. A type holder comprising the construction defined in claim 3 in which vertical longitudinally spaced sockets are provided in the interior face of the recessed vertical wall to receive the vertical ribs of type having bodies provided with such ribs.

5. A type holder comprising the construction defined in claim 3 presenting lugs projecting at each end of the holder by which it may be secured in position.

6. A printing chase comprising a rectangular frame having opposite side members provided with similar longitudinal

slots, a plurality of type holders each comprising a main bar extending transversely of the frame with its ends fitted in said slots, and a pair of auxiliary bars secured to the main bar and extending transversely of the frame between the side members, the said auxiliary bars being spaced from the main bar a distance equal to the depth of the type body and from each other a distance not less than the thickness of the main bar whereby the holders may be closely nested to bring lines of type held thereby close together by causing the main bar of one type holder to fit in between the auxiliary bar of the next type holder.

7. A type holder comprising a main bar and a pair of auxiliary bars secured to and parallel with the main bar, both spaced from the main bar a distance equal to the depth of the type body and from each other a distance not less than the thickness of the main bar.

8. A type holder comprising the construction defined in claim 7 in which the main bar extends at both ends beyond the auxiliary bars to provide means for securing the type holder in a printing chase.

9. A printing chase comprising a rectangular frame, a plurality of similar, laterally nesting, endwise reversible, vertically slotted type holders, and means for separately and individually securing the type holders to, and transversely of, the frame.

10. A printing chase comprising a rectangular frame, a plurality of similar laterally nesting, and endwise reversible type holders, each type holder having a rectangular opening extending longitudinally thereof and vertically therethrough to receive and support the type, and means for separately and individually securing the type holders to, and transversely of, the frame.

11. A printing chase comprising the construction defined in claim 10 in which vertical longitudinally spaced sockets are provided in the interior face of the longitudinal opening thereof to receive the vertical ribs of type having bodies provided with such ribs.

In testimony whereof, I have signed my name to this specification.

ALONZO KIMBALL MARSH.
